UNITED STATES PATENT OFFICE.

GEORGE RAMSEY, OF BROOKLYN, NEW YORK, ASSIGNOR TO ANCHOR CAP AND CLOSURE CORPORATION, OF LONG ISLAND CITY, NEW YORK, A CORPORATION OF NEW YORK.

CLOSURE CAP.

Application filed March 25, 1924. Serial No. 701,668.

The present invention relates broadly to closures and more especially to a friction cap adapted for use on glass containers and the like.

5 Various types of friction caps in use heretofore in the art have comprised devices made of sheet metal and the like wherein the friction elements were produced by displacing portions of the skirt of the cap to provide inwardly projecting friction members. In some cases the friction members comprised a continuous internal bead; in other cases the friction members were interrupted projections extending inwardly. In 10 the case of the inwardly projecting bead the range of variation in sizes of glasses to be sealed was quite small and after the cap was once removed it was stretched so that the cap became substantially ineffective as a re-seal. In the case of inwardly formed 15 projections the material in the skirt of the cap was usually stretched in applying the cap so that when the cap was removed the material therein was also so stretched that the cap became ineffective for re-sealing.

The present invention overcomes the difficulties of the known prior art by providing a friction seal in which the skirt of the cap is constructed to provide a yielding 20 constricting gripping portion which is springy in character and which may be removed and applied to containers a number of times without seriously affecting the effectiveness of the gripping action to form a seal. The cover portion of the cap is provided with an annular groove positioned a 25 short distance from its edge; and corrugations extend from this groove outwardly to the edge of the cover portion and downwardly to the bottom of the skirt. The corrugations in the zone between the annular groove and the edge of the cover portion permit this 30 zone to expand circumferentially, thereby enabling the annular groove to yield radially and allow the upper portion of the skirt to be displaced as a whole radially outward when the cap is applied to a suitable container. The corrugations in the skirt proper permit it to expand to a diameter 35 which is considerably greater than its normal diameter. This ability of the upper edge of the skirt to move bodily outward when the cap is applied to a container is a feature which particularly adapts the cap

for use upon grades of ware in which the 55 sizes of individual containers vary greatly from the standard size.

The great range of the elasticity in the skirt of the cap permits this cap to be used for re-sealing purposes a number of times 60 without seriously injuring the effectiveness of the cap.

The principal object of the present invention is to provide a friction closure cap capable of effectively closing containers that 65 are farther off size than those which it has heretofore been practicable to seal effectively.

Another object of the present invention 70 is a closure cap having the crown portion thereof constructed to yield radially and the skirt portion thereof constructed to yield circumferentially.

Another object of the present invention is 75 a closure cap having a circumferential groove in the crown thereof and radial grooves extending from said circumferential groove outwardly and into the skirt of the cap.

A still further object of the present invention is a closure cap having a substantial 80 flat cover portion with a circumferential bead adjacent the extremities of the cover portion and with outwardly and downwardly extending ribs which lead from said bead 85 to the lower edge of the skirt of the cap and with a sustaining member arranged in the skirt of the cap.

Other and further objects of the present 90 invention will in part be obvious and will in part be pointed out hereinafter by reference to the accompanying drawings in which like parts are represented by like characters throughout the several figures thereof.

It is realized that the present invention 95 may be embodied in constructions other than those herein specifically disclosed, therefore it is desired that the disclosure herewith shall be considered as illustrative and not in the limiting sense.

Figure 1 illustrates a cap in accordance 100 with the present invention seated upon a suitable container to form a sealed package.

Figure 2 is a detail sectional view through the upper part of Figure 1.

Figure 3 is an enlarged detail sectional view of one side of the cap on a container.

Figure 4 is a plan view of the cap.

Figure 5 is a detail sectional view of a smaller sized cap shown with a gasket inside of the cap.

Referring now more especially to the drawings, the cap A comprises a cover portion 1 provided with a circumferential groove 2 which is in the outer portion of the cover part and curved member 4 extending from said groove 2 outwardly and down-
wardly in the form of a distorted ogee curve which terminates in a wire edge 5 in which the free edge of the metal of the cap is turned inward to prevent rusting and at the same time to form a substantially in-
elastic fulcrum member against which the curved members 4 may act. The curved members 4 are formed by curved corruga-
tions which extend from the groove 2 to the wire edge 5. These corrugations are elastic
or stretchable at substantially right angles to the length of the corrugations, therefore, while the members 4 are reinforced in a radial direction and act substantially as levers, these members form a part of the skirt of the cap, which is elastic in a circumferential direction.

When the cap is forced over a suitable container B of glass or the like, the corrugated zone in the cover portion which lies between the edge of the cover portion and the annular groove 2 expands or is circumferentially enlarged thereby permitting the annular groove 2 to act as a radial expansion zone and permit the upper edge of the skirt proper to move bodily outwardly. The corrugations in the skirt permit it to expand to give it any necessary increased circumference. This construction which permits the upper edge of the skirt to move bodily outward allows the cap to be applied even though the container should be considerably oversize. The action of the constricting force of the skirt due to its own resiliency combines with the resilient force of the annular expansion zone in the cover portion, which urges the upper portion of the skirt to its normal position with respect to the center of the cover portion, to hold the cap securely on the container.

Figure 5 illustrates a slight variation in the embodiment of the invention and shows the cap as applied to the neck of a catsup bottle, or the like, in which the interior of the cap is provided with a gasket 9 adapted to be seated against the end of the container. The side wall of the container as at 10 is undercut slightly so as to permit the cap to slightly underlock with the upper portion of the container having a bead 11 thereon to securely hold the cap in position. An annular protecting bead 12 may be provided on the side wall of the container to form a convenient means by which the cap may be forced from the container by inserting a coin or suitable tool at 14 between

the bead and the wire edge of the cap, and prying the cap off the end of the container.

From the foregoing it will appear that the present invention provides a secure friction cover cap which may be sealed and unsealed a number of times without injury either to the container or the cap.

Having thus described my invention, what I claim is:—

1. A closure comprising a cover portion, and a skirt depending from said cover portion, said skirt being corrugated to permit circumferential expansion, and said cover portion being provided with an annular expansion zone to permit the top of the skirt to move radially as a whole with respect to said cover portion when the closure is applied to a suitable container.

2. A closure comprising a substantially circular cover portion, and a skirt depending from said cover portion, means in said skirt to permit circumferential expansion of said skirt, and said cover portion being provided with an annular expansion zone to permit the top of the skirt to move radially as a whole with respect to said cover portion when the closure is applied to a suitable container.

3. A closure comprising a cover portion, and a skirt depending from said cover portion, said skirt being corrugated to permit circumferential expansion, and expansion means in said cover portion to permit the top of the skirt to move radially with respect to said cover portion when the closure is applied to a suitable container.

4. A closure comprising a cover portion, a skirt depending from said cover portion, said skirt being corrugated to permit circumferential expansion and said cover portion being provided with an annular expansion zone to permit the top of the skirt to move radially with respect to said cover portion when the closure is applied to a suitable container, and means to prevent the expansion of the lower edge of the skirt.

5. A closure comprising a substantially circular cover portion, and a skirt depending from said cover portion, said skirt and the outer edge of the top being corrugated to permit circumferential expansion, and said cover portion being provided with an annular groove contiguous to said corrugations to permit the upper part of the skirt to move radially with respect to the remainder of said cover portion when the closure is applied to a suitable container.

6. A closure comprising a cover portion, and a skirt depending from said cover portion, said skirt and the outer edge of the top being corrugated to permit circumferential expansion, and said cover portion being provided with an annular groove adjacent said corrugation to permit the upper part of the skirt to move radially with re-

- spect to the remainder of said cover portion when the closure is applied to a suitable container and means to hold the lower edge of the skirt against expanding.
- 5 7. A closure comprising a cover portion, and a skirt depending from said cover portion and having a cross-section comprising an ogee curve, said skirt being corrugated to permit circumferential expansion, and said cover portion being provided with at least one annular corrugation and corrugations extending outwardly therefrom to permit a part of the skirt to move radially with respect to said cover portion when the closure is applied to a suitable container.
- 10 8. A closure comprising a substantially circular cover portion, and a skirt depending from said cover portion and having a cross-section comprising an ogee curve, said skirt being corrugated to permit circumferential expansion, and said cover portion being provided with at least one annular groove to permit a part of the skirt to move radially with respect to said cover portion when the closure is applied to a suitable container, said corrugations extending into the outer wall of said groove.
- 15 9. A closure comprising a cover portion and a skirt depending from said cover portion, said skirt being corrugated to permit circumferential expansion, and said cover portion being provided with an annular expansion zone to permit part of the skirt to move radially with respect to said cover portion when the closure is applied to a suitable container, and a gasket adapted to form a seal when the closure is applied to a receptacle.
- 20 10. A closure comprising a cover portion and a skirt adapted to embrace the side wall of a receptacle adjacent the mouth thereof, said skirt having expansion zones to permit it to embrace a receptacle larger than the normal size of the skirt, and an expansion zone contained in said cover portion to permit the outer periphery of said cover portion to move perpendicularly with respect to the side wall of a receptacle when the closure is applied to the receptacle.
- 25 11. A closure comprising a cover portion, and a skirt adapted to embrace the side wall of a receptacle adjacent the mouth thereof, said skirt having expansion zones to permit it to embrace a receptacle larger than the normal size of the skirt, and an expansion zone contained in said cover portion to permit the upper extremity of said cover portion to move perpendicularly with respect to the side wall of a receptacle to which the closure is applied, and means in the form of a rolled edge to prevent expansion of the lower edge of the skirt.
- 30 12. A closure comprising a cover portion and a skirt adapted to embrace the side wall of a receptacle adjacent the mouth thereof, said skirt being corrugated to permit it to embrace a receptacle larger than the normal size of the skirt, and an expansion zone contained in said cover portion to permit the extremity of said cover portion to move perpendicularly with respect to the side wall of a receptacle to which the closure is applied.
- 35 13. A closure comprising a cover portion and a skirt adapted to embrace the side wall of a receptacle adjacent the mouth thereof, said skirt having expansion zones to permit it to embrace a receptacle larger than the normal size of the skirt, and an expansion zone contained in said cover portion to permit the extremity of said cover portion to move perpendicularly with respect to the side wall of a receptacle to which the closure is applied, and a gasket adapted to form an end seal when the closure is applied to a receptacle.
- 40 14. A package comprising a container closed by a cap comprising: a cover portion covering the mouth of the container; a skirt depending from said cover portion and embracing the contained adjacent the mouth thereof, said skirt being stressed and exerting a constricting force on the container wall and the upper portion of the skirt being radially displaced as a whole from its normal position with respect to the center of the cover portion.
- 45 15. A package comprising a container closed by a cap comprising: a cover portion covering the mouth of the container; a skirt embracing the container adjacent its mouth, the upper portion of the skirt being displaced as a whole from its normal position with respect to the center of the cover portion; and non-expanding means holding the lower edge of said skirt in its normal position with respect to the center of the cover portion.
- 50 16. A package comprising a container closed by a cap comprising: a cover portion covering the mouth of the container; a skirt embracing the container adjacent its mouth, the upper portion of the skirt being displaced as a whole from its normal position with respect to the center of the cover portion; means included in said cover portion to urge said skirt toward its normal position with respect to the center of the cover portion; and non-expanding means holding the lower edge of the skirt in its normal position with respect to the center of the cover portion.
